UNITED STATES PATENT OFFICE.

ARLINGTON L. BALL, OF TIPTON, INDIANA.

FUEL-FEED-CONTROLLING DEVICE.

Application filed May 16, 1923. Serial No. 639,347.

This invention relates to improvements in fuel feed-controlling devices, and it has more particular reference to a device of this kind adapted for feeding liquid-hydrocarbon to burners for heating hovers and the like.

The primary object of my invention is the provision of a liquid-fuel feed-controlling device in which the usual regulating needle and parts associated therewith for adjusting the needle, are dispensed with.

Another object of my invention is to provide a device of this kind whereby the liquid fuel is fed from a part to which it is delivered by capillary attraction, the fuel being allowed to drip from said part in regulated quantities, depending on the position of said part.

A further object of my invention is to provide a liquid-fuel feed-controlling device, including an element which absorbs the fuel, and means for delivering the fuel from said element at any desired speed within certain limits.

A still further object of my invention is the production of a device of this kind by means of which the liquid fuel can be fed in the desired quantities and be so maintained, and one which is inexpensive to manufacture, and absolutely safe.

With the above and other objects in view, the invention consists in the novel features of construction and in the arrangement and combination of parts to be hereinafter described and more particularly pointed out in the subjoined claims.

In the drawings:—

Fig. 1 is an elevation of my improved liquid-fuel feed-controlling device and parts associated therewith for feeding liquid fuel thereto and delivering the same in regulated or controlled quantities therefrom.

Fig. 2 is an enlarged vertical section taken on line 2—2, Fig. 1.

Fig. 3 is a horizontal section taken on line 3—3, Fig. 2.

Fig. 4 is an enlarged vertical section taken on line 4—4, Fig. 2, looking in the direction of the arrow crossing said line.

Fig. 5 is a detached perspective view of the movable control element.

Fig. 6 is a detached perspective view of the cover of the casing in which said control element is located.

Referring to the drawings in detail, the reference numeral 7 designates a support or

bracket which has a small cup-like fuel-receiver 8 formed at one end thereof and into which is threaded a feed pipe 9 adapted to be led to a burner to which liquid fuel, in controlled quantities, is to be delivered by means of this improved liquid fuel controlling device. The bracket 7 may be supported by means of the feed pipe 9, or in any other suitable manner, and in turn it supports a liquid fuel tank or can 10, which is open at the top and supports an inverted bottle or other fuel container 11, said bottle or container having a neck 12 depending axially therefrom and extending a distance into the tank or can. The lower end of this neck determines or may determine the level of the liquid fuel in the tank or can 10. The bottle or container 11 is filled with the liquid fuel and when inverted and supported by the tank or can serves to supply the latter with fuel and maintain a predetermined fuel level until the contents of the bottle or container is fully delivered.

The tank or can 10 is preferably cylindrical in cross section and the bottle or container is of similar formation; however, it may be otherwise formed, if desired. In the cylindrical, or what I shall term the side wall, of the tank or can, an opening is formed above the level of the liquid fuel therein, and fixed in this opening is a tube 13, which extends a distance outwardly and inwardly from said cylindrical side wall, the outer end being flanged and having a controller casing 14 mounted thereon. The controller casing as shown in Fig. 4 is cylindrical in cross section, and the tube 13 enters said casing off-center, preferably to one side and above the axis of said casing.

15 designates a movable control element in the form of an angular tube or tubular elbow, one arm 16 of which is entered in the fixed tube 13 and the other arm 17 of which is adapted to be swung in an arc of 100 a circle within the control casing 14.

18 designates an absorbent element which may be in the form of twisted strands of cotton or other suitable material, this absorbent element being comparatively long, 105 and one end thereof is inserted into the movable control element 15, the extremity at said end projecting out of the free end of said movable control element and being retained within a tapering adjunct 19 in the form of thin metallic straps crossing each other and bent into substantially V-shape,

the free ends being soldered or otherwise secured to the free end of said movable control element or tubular elbow 15. Secured to said adjunct, or cage as it may be termed, 5 is a drip element 20 in the form of a comparatively thin bar or needle soldered to the outer end of the cage 19 and disposed at an angle thereto, the free end of said drip element or needle being always the low point 10 of said needle.

At the lowest point of the cylindrical wall of said control casing 14, an opening 21 is formed, and extending through said opening is a drip needle 22, somewhat smaller in 15 diameter than the opening 21 so that liquid fuel dripping from the needle 20 will be transferred to the needle 22 and from the latter drip to the cup-like fuel receiver 8 formed at the outer end of the bracket 7, 20 the fuel delivered into said receiver then passing through the feed tube 9 to a burner in the usual way. The needle 20 at the outer end of the movable control element 15, may therefore be termed a transfer needle, 25 as will be hereinafter more particularly explained.

When positioning one end of the absorbent element in the movable control element 15, the major portion of this absorbent element hangs freely from said control element, 30 and in placing the control element in position, it is necessary to first pass the hanging or free portion of said absorbent element through the fixed tube 13 fastened to the 35 peripheral or side wall of the tank or can 10, after which the arm 16 of the movable control element or tubular elbow 15 may be inserted into the fixed tube 13. The inner or free portion of the absorbent material is 40 then passed through supporting rings 23 formed on arms 24 soldered to the bottom of the tank or can 10, these arms rising from said bottom to elevate the supporting rings. That portion of the absorbent material extending into the tank or can is arranged in a sort of loop formation so that 45 all parts thereof from a point near the inner end of the fixed tube 13 are submerged in the liquid fuel within said tank or can.

50 The control casing 14 is open at its outer end and it has a segmental flange 25 rising from the edge of its cylindrical wall along the lower portion thereof, as indicated by dotted lines in Fig. 4. This prevents the 55 escape of liquid fuel from the control chamber in the event that there should be an accumulation of the same therein. The open end of said control casing is closed by a cover 26 having an annular flange 27 fitting 60 around the outer marginal portion of the control casing 14. This cover is fastened in place by screws 28, one of which passes through the rear wall of the control casing and has a nut 29 applied thereto and the 65 other being threaded into a nut 30 soldered

to the inner or end wall of said control casing, as best shown in Fig. 4.

31 designates a regulating lever pivotally secured to the outer side of the cover 26 of the control casing, which cover, in a broad sense, may be considered as part of said control casing. The outer end of said lever is pointed, as at 32; and near said pointed end a handle 33 is provided for conveniently manipulating said lever. The pivot 75 34, by means of which said lever is pivotally secured to the cover 26, extends through a second lever 35 arranged at the inner side of the cover, said pivot serving as a center on which both the regulating lever 31 and the lever 35, which may be referred to as an actuating lever, swing. The actuating lever 35 is somewhat shorter than the regulating lever 31, and it is provided with an inwardly extending pin 36.

On the arm 17 of the control element or tubular elbow, a guide strap 37 is arranged, said strap being parallel with said arm and the ends thereof being soldered or otherwise fastened to said arm, as at 38. The pin 36 of the actuating lever 35 enters the parallel-sided space between said strap and the arm 17 and therefore on swinging said levers, said pin 36 will swing the arm 17 of the control member either to the right or left, the lowermost position of said arm being indicated by full lines in Fig. 4, and the highest position by dotted lines in said figure.

On the outer side of the cover 26 a segmental guide rib 40 is formed and along 100 said guide rib, indication marks are provided to disclose the degree of feed given the liquid fuel. Opposite the high point of said guide rib the word "Off" is arranged. Opposite the low point thereof the word "On", and between the words "Off" and "On", numerals 1, 2, 3 and 4, 105 designating different stages of feeding fuel; the numeral 1 indicating approximately the slowest feed, and each increasing numeral 110 a larger feed until the full supply is being fed, at which time the lever points to the word "On". When the lever is swung to point to the word "Off", the control element 15 will be in the position indicated by dotted lines in Fig. 4, and under such 115 conditions that portion of the absorbent element or wicking extending through the fixed tube and into and through the control element 15 will be above the level of the liquid fuel within the tank or can 10. No liquid fuel will, under such conditions, be fed into the control casing 14. However, when swinging the arm 17 of said control element downwardly by reason of the actuating lever being swung from the word "Off" to the numeral 1, a small portion of the wicking 18 within the control element 120 will be below the level of the liquid fuel in the tank or can 10, with the result that a 125

very small quantity of fuel will drip from the wicking and be delivered into the control casing so as to escape through the opening 21 of the latter, in doing which, it 5 passes down along the needle 22 in the same proportion and at the same speed that it was transferred to said needle 22 from the needle 20. The needles 20 and 22 are of the same diameter, and thus assure an even 10 dripping of the liquid fuel from the needles 20 and 22.

Further lowering of the regulating lever 31 positions a larger area of wicking within the fuel control casing below the level 15 of the liquid within the tank or can 10, and allows proportionately larger quantities of liquid to be transferred from the needle 20 into the casing to be delivered by the needle 22 to the receiving cup 8 for final 20 delivery to the burner. It is, of course, understood that as the regulating lever 31 is swung in one or the other direction, the actuating lever 35 will be swung in a corresponding direction, causing the actuating 25 pin 36 to move in an arc of a circle and either force the arm 17 of the tubular elbow or control element upwardly, or pull said arm downwardly by reason of its action against the strap 37.

Having thus described my invention, what I claim is:—

1. The combination with a tank having liquid fuel therein and an opening in its side wall above the level of said liquid fuel, 35 of a control casing outside of said tank, an elongated absorbing element extending from the liquid fuel in said tank outwardly through the opening in the latter and having its outer end adjustably arranged in said control casing to deliver liquid fuel into said casing in different quantities according to the adjustment of said absorbent element therein, and means for delivering the liquid fuel from said control casing, drop by drop.

2. The combination with a tank having liquid fuel therein, of a tube positioned in said tank above the level of the liquid therein, a control element pivotally mounted in said tube, an elongated absorbing element having a portion thereof submerged in the liquid fuel in said tank and a portion thereof carried by said control element, and means for swinging said control element with said tube as its center to bring the feeding end of said control element above or at any desired point below the level of the liquid fuel within said tank.

3. The combination with a liquid fuel tank, of a tube secured in the side wall thereof, a control casing with which said tube communicates, a tubular elbow having one arm thereof rotatable in said tube and its other arm extending therefrom, an absorbent element having part thereof sub-

merged in the liquid fuel in said tank and part thereof passing through said tubular elbow, and means manipulated from the outside of said control casing for swinging said tubular elbow in an arc of a circle. 70

4. The combination with a liquid fuel tank, of a tube secured in the side wall thereof and extending outwardly and inwardly therefrom, a control casing carried by said tube, a tubular elbow having one 75 arm thereof rotatable in said tube and its other arm extending therefrom within said control casing, absorbent material in elongated form extending through said tube and tubular elbow and having a portion extending from said tube into the liquid fuel in said tank, a regulating lever at the outside of said control casing, and means between said regulating lever and said tubular elbow for swinging the latter in an arc of a 80 circle to position all portions of the absorbent material therein above the level of the liquid fuel in said tank or to move different portions of said material below the level of said liquid fuel. 85

5. The combination with a liquid fuel tank, of a control casing adjacent said tank, a tubular elbow arranged within said control casing to swing in an arc of a circle, absorbent material in elongated form extending from the liquid fuel in said tank outwardly into said tubular elbow and projecting therefrom, a regulating lever pivotally secured to one wall of said control casing, an actuating lever operated by said regulating lever, and means between said actuating lever and said tubular elbow for swinging the latter in opposite directions. 95

6. The combination with a liquid fuel tank, of a control casing adjacent said tank having an opening at a low point, an absorbent element extending from the liquid fuel in said tank outwardly into said control casing and having an angular portion within said casing adapted for movement in an arc of a circle, and means for swinging said angular portion in an arc of a circle to move the same above the level of the liquid in said tank or in any desired proportion beneath said level. 105

7. The combination with a liquid fuel tank, of a control casing adjacent said tank having a liquid fuel escape opening, an elongated absorbent element extending from the liquid fuel in said tank outwardly into 120 said control casing and having an angular portion within said casing, means enclosing part of said angular portion, said angular portion having its outer extremity exposed and means for swinging said angular portion in an arc of a circle to position the exposed extremity thereof above the level of the liquid fuel in said tank or in any desired proportion beneath said level. 125

8. The combination with a liquid fuel 130

5 tank, of a control casing adjacent said tank having an opening and a drip needle extending from said opening, a tubular elbow 10 pivotally mounted in said control casing 5 above and to one side of the axis thereof, 15 an elongated absorbent element extending from the liquid in said tank outwardly into said tubular elbow and projecting from the free end of the latter, a transfer needle carried by said tubular elbow from which fuel 20 drips in quantities delivered by said absorbent material, and means for swinging said tubular elbow in an arc of a circle.

9. The combination with a liquid fuel 15 tank having liquid fuel therein, of a control casing adjacent said tank open at one end and having a cover secured to said open end, said casing having a liquid fuel escape 20 opening and a needle of smaller diameter than said opening extending therethrough, a 25 tubular elbow arranged for swinging movement within said control casing and having a cage at its outer end, and a transfer needle carried by said cage, an elongated absorbent 30 element extending from the liquid fuel in said tank outwardly through said tubular elbow and into the cage at the outer end of said elbow, and means on said cover for swinging said tubular elbow to position said transfer needle at different elevations.

10. The combination with a liquid fuel tank, of a control casing adjacent said tank cylindrical in cross section and open at one end, said casing having an upstanding flange 35 at its open end extending along the lower portion thereof and an escape opening at its lowest point, a cover secured to said casing for closing the open end thereof, a tubular elbow in said control casing having one 40 arm adapted to swing in an arc of a circle,

an elongated absorbent element extending from the liquid fuel in said tank into and through said tubular elbow and projecting from the free end of its swinging arm, a 45 cage at the outer end of said swinging arm 50 confining the projecting portion of said absorbent element, a transfer needle on said cage receiving the liquid fuel from said absorbent element, a needle extending through the escape opening in said control casing 55 and of smaller diameter than said opening, a regulating lever pivotally secured to the outer side of said cover off center thereof, an actuating lever at the inner side of said cover operated by said regulating lever, and a pin extending inwardly from said actuating lever and engaging said tubular elbow to swing the same in an arc of a circle when said regulating lever is actuated.

11. The combination with a liquid fuel 60 tank, of a control casing adjacent said liquid fuel tank, a tubular elbow within said control casing having one arm thereof serving as a pivot and the other arm extending 65 therefrom within said control casing, said last-mentioned arm having a strap secured thereto providing a parallel-sided slot, a cover for said control casing, a regulating lever secured to the outer side of said cover off center thereof, an actuating lever at the 70 inner side of said cover having its axis coincident with that of said regulating lever and being provided with an actuating pin extending inwardly therefrom, said pin being 75 adapted to enter said parallel-sided slot, and means to deliver liquid fuel from said control casing.

In testimony whereof I affix my signature.

ARLINGTON L. BALL.
